UNITED STATES PATENT OFFICE.

JOHN McMULLEN, OF BUFFALO, NEW YORK, ASSIGNOR TO E. PAYSON SMITH, OF SPRINGFIELD, ILLINOIS.

DRAFT-KEY ANCHOR.

Application filed July 27, 1925. Serial No. 46,235.

My invention relates to means for retaining or anchoring the usual coupler or draft keys in place against accidental removal and loss; the invention contemplating a structure adaptable for anchoring one or more draft keys, namely the coupler key as well as the key for the draft yoke or rigging.

One object of my invention is the provision of means of a character adapted to provide a firm or positive anchor for the keys, while at the same time enabling easy application to the present day standard type of cars and draft rigging and permitting ready release and removal of the draft keys should occasion require; the construction being such as to permit use of the rivet-holes and rivets at present employed in standard car construction.

The above enumerated objects and the advantages of my invention will all be more readily comprehended from the following detailed description of the constructions illustrated in the drawings, wherein:

Figure 1 is a plan view showing the application of one form of my invention to a coupler key; portions of the center sill members and coupler only being shown.

Figure 2 is a side elevation of a portion of the center sill and striking casting with my improved anchoring means shown in Figure 1; the coupler being omitted.

Figure 3 is a vertical sectional view taken substantially on the line 3—3 of Figure 2.

Figure 4 is a detail view in perspective of the latch member or key employed in the construction shown in Figure 1.

Figure 5 is a perspective view of the latch member holder or bracket.

Figure 6 is a sectional plan view of a portion of one member of a center sill and draft key, showing a modified form of my invention.

Figure 7 is a side elevation thereof.

Figure 8 is a view looking at the right hand end of the construction shown in Figure 7, with the striking casting removed and the draft key broken away.

Figure 9 is a detail perspective view of the latch member employed with the construction shown in Figure 6.

Figure 10 is a side elevation of the form shown in Figures 6 and 7, illustrating its application to a form or draft rigging employing two draft keys.

Figure 11 is a perspective view of the type of latch member holder or bracket employed in Figures 6 and 10.

In the exemplifications of the invention and as disclosed in Figure 1, the usual center sill members are shown at 10, 10, between which the shank of the coupler shown at 11 is located. The center sill members are usually reinforced by portions of the striking casting, shown at 12 or by cheek plates riveted to the center sill members; but as these elements form no part of my invention, a detailed description need not be entered into.

The center sill members (as well as the striking casting extensions or the cheek plates were used) are provided with registering slots disposed through the web of the sill members as shown at 13, (and in dotted lines in Figure 2) adapted to receive the draft key 14 whereby the coupler 11 is yieldingly secured to the car underframe; the slots being of length greater than the transverse dimensions of the keys.

These coupler or draft keys 14 are usually provided at one end with a head as shown at 16, while the opposite and somewhat tapered end has heretofore been provided with a small opening to receive a cotter-pin for the purpose of preventing accidental removal of the keys. During operation, these cotter-pins frequently are sheared off by constant vibration and jarring of the mechanism which causes the cotter-pins to be forced against the center sill member, with the result that the cotter pins are sheared off and the coupler or draft keys are frequently lost and a serious disarrangement of the draft rigging brought about.

My invention, as shown in Figure 1, comprises an inverted U-shape member 17 having the horizontally disposed portion 18 adapted to extend lengthwise of the center sill and terminating at the ends in the two parallel and vertically disposed bracket or pocket forming portions 19, 19; the member 17 being so formed and provided with rivet holes spaced to register with the spacing of the rivets in the center sill in order that the same rivets may be employed for securing the member 17 in place; thereby saving time and expense. The portions 19 extend out laterally from the base or connecting portion 18 and therefore outwardly

from the center sill member 10, as shown in Figure 3, into a vertical plane beyond the plane of the head of the draft or coupler key 14, sufficient to receive a latch key or anchor member 20 of comparative width as shown in Figure 4; the lower ends of portions 19 terminating in rivet receiving bosses 19^a.

The latch member 20 is intended to extend through both bracket portions 19 and transversely of the head 16 of the draft key, namely in the same horizontal plane as the draft key and rests on the shoulders 19^b.

The latch member 20 is provided at each end with depending lips or projections 21, 21, which are adapted to engage with the outer sides of the bracket portions 19, 19 as shown in Figure 2; while one end of the latch member 20 is enlarged vertically so as to provide the raised portion or lug 22. The vertical width of the latch member or plate 20 at the end provided with the raised portion 22 and forward of the depending lip 21, is substantially equal to the vertical dimensions between the shoulders 19^b and the upper ends of the brackets 19. The major portion of the latch member is preferably of equal vertical dimensions throughout, with the vertical width at the other end of the latch member (namely the one without the raised portion) to the bottom of the lip or projection 21 being somewhat less than the vertical dimensions of the opening through the bracket members 19 in order that the latch members may freely pass through said openings. The latch member 20 is inserted through the openings so as to have the depending projections or lips 21, 21 extend on the outer sides of the member 17; the latch member dropping down to the bottom of the openings in the bracket portions 19 so that the lips 21 will under normal conditions prevent longitudinal movement of the latch member. The raised portion or lug 22 is of such height that the distance between it and the upper portion of the yoke or bracket portion 19 is less than the length of the depending lip 21, with the result that accidental displacement of the latch member through vibration will be prevented. As a precaution, however, against any accidental displacement of the latch member 20, I show the end of the latch member which has the raised portion 22, provided with an opening at 23 which is adapted to register with an opening in a lobe or ear 24 formed integral with one of the bracket portions 19 in order that a cotter or other suitable pin may be inserted therethrough as shown at 25 in Figure 1.

As the latch member 20 is not subjected to longitudinal strains or movement, it is apparent that the cotter-pin 25 will not be subjected to any shearing strains. As is apparent from the construction shown, the

latch member or plate 20, which is of relative thickness, will be firmly held across the path of the draft or coupler key 14 and in close proximity to the head portion 16 thereof, so that longitudinal movement of the draft key is impossible and all possibility of displacement or loss of the draft or coupler key is eliminated.

In Figures 6 to 8 I show a modification of my improved draft key retaining or anchoring means, wherein the bracket or pocket-forming portions constitute separate members as shown at 26 and are not formed integral as in the single piece member previously described. The members 26 are provided with base portions or lobes apertured to receive bolts or rivets whereby the same may be secured to the center sill member 10 as shown. It is apparent that the members 26 may be spaced apart so as to have their apertured lobes register with certain of the rivet holes employed in standard car construction for securing other elements in place. The members 26 have the lateral bowed or outwardly disposed intermediate portions 27. The intermediate portions 27 are provided with openings therethrough, like the bracket portions 19 in the previously described construction; and these portions extend into a vertical plane beyond the vertical plane of the head 16 of the coupler or draft key 14. The openings are preferably offset at the point indicated at 28 so as to provide a socket for the latch or anchoring member 29 which is of length sufficient to extend through the openings of both members 26 in a direction transversely of the coupler key. The latch member 29, shown in this modification, is preferably provided at one end with the outwardly turned hook portion 30, which not only provides a stop against the too far insertion of the latch member, but is formed so as to overlap or hook over the intermediate portion of the adjacent member 26 as shown in Figures 6 and 7. With the hook end 30 in lapping relation with the intermediate portion of the adjacent member 26, it is evident that the latch member 29 will be held against lateral movement and therefore normally held in slight spaced relation with the head 16 of the draft or coupler key 14. The opposite or tail end of the latch member 29 is shown provided with an elongated slot 31 adapted to receive a split pin 32 as shown in Figures 7 and 8.

In Figure 10 I illustrate the application of the modification shown in Figure 6 to a situation where two draft keys are employed; the construction in Figure 10 merely consisting in the use of a third member 26 shown in Figure 11 and the employment of a longer latch member 29^a; the intermediate member 26 being employed as a reinforcement for the long latch member 29^a. The

construction of the elements and their operation are the same as those previously described.

With the constructions shown and described, it is evident that a positive anchor or retaining means is provided for the draft or coupler keys which not only is adapted to withstand any of the stresses or strains encountered through the longitudinal movement of the draft keys, but which is of such construction that accidental removal of the anchoring or latch mechanism is impossible. At the same time a device is provided which can readily be secured to the center sills and which is adapted to utilize certain of the rivets which are employed for securing either the extensions of the striking casting between the center sills or for securing the cheek plates or reenforcing elements in place, and thus obviates the necessity of additional rivet holes in the center sill member. Furthermore, my improved anchoring means are of such construction that, when occasion requires, the latch members may be quickly removed to permit removal of the draft keys; the latch members, as shown in the drawings, extend throughout the length of the draft

key slots 13, so that the draft keys will at all times be properly anchored or held in place regardless of their position in the slots 13.

I have shown and described what I believe to be simple adaptations of my invention which have been described in terms employed merely as terms of description and not as terms of limitation, as structural modifications may be made without, however, departing from the spirit of my invention.

What I claim is:

A draft key anchor comprising, in combination with the draft mechanism of a railway car including draft sills having key-receiving openings and a draft key having an enlarged head at one end, said key being disposed transversely through the key receiving openings, separate bracket-forming means secured to a center sill member of the car and arranged on opposite sides of the openings, and means, against which the head of the draft key is adapted to bear, 40 45 50 55 60 65 70 75 80 85 90 95 100 105 110 115 120 125 130 135 140 145 150 155 160 165 170 175 180 185 190 195 200 205 210 215 220 225
